COLLAPSIBLE TABLE WITH LOCK MEANS
FOR PAIRED LEGS

Bertis F. Hamilton, Columbus, Ind.

Application July 23, 1948, Serial No. 40,356

1 Claim. (Cl. 311—84)

1

My invention relates to folding tables and has for its object the provision of an all-metal table which can be simply and economically manufactured, which will have an attractive appearance, and which will be sturdy and rigid when extended.

In carrying out my invention, I form the table with a sheet-metal top having a down turned peripheral flange. A pair of channel members are disposed against the lower surface of the top and are secured in place by attachment of their ends to the peripheral top-flange. The legs are formed in pairs, conveniently of metal tubing, the legs of each pair being rigid with a shaft pivotally supported from the channel members. Associated with each pair of legs is a U-shaped brace or yoke the ends of which are respectively pivoted to the legs and the intermediate portion of which is received in slots in the vertical walls of the channels. Such slots are formed to hold the legs extended or to permit them to swing against the lower face of the table. The legs are arranged so that when collapsed they will cooperate with other elements of the table and be releasably retained in collapsed positions.

The accompanying drawings illustrate my invention: Fig. 1 is a vertical longitudinal section through the table with the legs extended; Fig. 2 is a plan view showing the lower side of the table with the legs collapsed; Fig. 3 is a fragmental view generally similar to Fig. 1 but on an enlarged scale; Fig. 4 is a horizontal section on the line 4—4 of Fig. 3; Fig. 5 is a fragmental section on the line 5—5 of Fig. 2, showing the legs in collapsed condition; and Fig. 6 is a section on the line 6—6 of Fig. 2.

The table shown in the drawing comprises a top 10, of generally rectangular shape, having at its edges a downwardly extending peripheral flange 11. Desirably, the top and its flange are formed as a one-piece metal stamping. Extending longitudinally of the table and beneath the top are a pair of spaced reinforcing members 12 of channel cross-section having the ends of their flanges turned outwardly and secured to the flange 11 of the table top as by means of rivets 13. Near their ends the two channels are provided in their flanges with upwardly opening, transversely aligned notches 14 which receive rock-shafts 15 and 16. The rock shaft 15 has secured to its ends a pair of parallel inner legs 17 while the rock shaft 16, which is longer than the shaft 15, has secured to its ends a pair of outer legs 18. The arrangement is such that when the legs are collapsed they occupy gener-

2

ally co-planar positions with each inner leg disposed between the adjacent channel 12 and the outer leg 18. Conveniently, the shafts 15 and 16 are formed of tubular material which is distorted adjacent the inner flange of the channels 12 to provide abutments 19 which, by engagement with the channels, limit movement of each shaft axially of itself.

The bottoms of the notches 14 are semi-circular, conforming to the curvature of the shafts which they receive, and the shafts are held in the notches by U-shaped stirrups or yokes 20 each of which overlies its associated shaft within the channel 12 and is provided with out-turned feet 21 which are secured to the web of the channel 12 as by rivets 21'.

For the purpose of holding the legs extended, I employ braces 22 and 23, each conveniently formed of metal rod bent into a general U-shape. 10 The intermediate portion of such rod is received in slots 24 formed in the flanges of the channels 12, while the ends of each brace are turned outwardly into substantial alignment for reception in holes in the inner faces of the associated legs. 15 At the outer end of each slot, it is provided with a short extension 24' (Fig. 3) inclined downwardly and inwardly of the table to receive and retain the intermediate portion of the associated brace when the table is extended.

To insure entrance of the intermediate section of the brace into the slot-extensions 24' when the table is extended, and to insure that the brace will remain in the slot extensions until it is desired to collapse the table, I employ springs 25. Each of such springs is conveniently formed of a length of wire doubled on itself and having its ends formed to provide hooks 26 received in holes in the inner side of the adjacent stirrup 20. At its inner end the spring is provided with offsets 27 which extend outwardly through the slots 24 and with vertical offsets 28 which, by engagement with the flanges of the channels 12, locate the free end of the spring laterally. In side elevation each spring 25 is so formed that with the offsets 27 in engagement with the tops of the slots 24 the intermediate portion of the spring extends across the slot-extensions 24' in position to force the associated brace (22 or 23) into engagement with the bottoms of such extensions. In addition, the spring should be so formed that engagement with the bottom of the channel 12 will hold the offsets 27 against the tops of the slots 24 when the table is collapsed.

To prevent the brace 23 from interfering with 50 movement of the legs 17 to collapsed position,

its sides are bent downwardly near their outer ends, as indicated at 30 in Fig. 3; and for the purpose of providing similarity of appearance, the outer ends of the sides of the brace 22 may be similarly bent downwardly as indicated at 31 in Fig. 1. As will be clear from Fig. 5, the bends 30 at the outer ends of the sides of the brace 23 permit the inner legs 17 to swing into generally co-planar relationship with the outer legs 18 when the table is to be collapsed.

Desirably, the outer legs 18 are so mounted at the ends of the shaft 16 that they diverge slightly, as shown in Fig. 2, so that some inward displacement of the outer ends of the legs 18 will be necessary to enable them to enter within the flange 11 on the table top. The dotted lines in Fig. 2 indicate the normal, or unstressed, positions of the outer legs 18, while the full-lines show the legs as forced together to enter into overlapping relationship with the flange 11. As a result of this arrangement, when the legs 18 are collapsed their outer ends bear frictionally against the faces of the flange 11, thus holding the outer legs in collapsed condition. To retain the inner legs in collapsed position, the brace 23 is so shaped at the bends 30 that it will bear resiliently as a detent on the outer sides of the legs 17 when they are moved to collapsed position.

The table is shown collapsed in Figs. 2, 5, and 6, the outer legs being held in collapsed position by friction with the inner faces of the flange 11 and the inner legs being held in position by engagement with the outer end portions of the brace 23, as above set forth. The flange 11 is desirably wide enough that the legs lie within its vertical limits when collapsed. To extend the table, the inner legs and then the outer legs are swung outwardly about the axis of the respective shafts 15 and 16. In this movement of the legs 17 the intermediate portions of the braces 22 and 23 move outwardly in the slots 24 eventually engaging the springs 25 which urge them downwardly. When the intermediate brace-portions move into alignment with the extensions 24' of the slots 24, the springs 25 force them downwardly into such extensions and thus lock the legs in extended position. When the table is to be collapsed, the braces 22 and 23 are forced upwardly about their axes of attachment with the legs until their intermediate portions clear

the slot-extensions 24', whereupon the legs may be swung to collapsed position.

I claim as my invention:

A collapsible table, comprising a top having a depending peripheral flange, inner and outer pairs of legs pivotally mounted on said top near opposite ends thereof and swingable between collapsed positions within said flange and extended positions in which they project downwardly to support the top, means for releasably holding the legs in their extended positions, said outer legs lying between the inner legs and said flange when the legs are in collapsed positions, and being so spaced that their free ends frictionally engage said flange when the outer legs are in collapsed position, the means for holding the outer legs in their extended positions including a generally U-shaped brace having an intermediate portion and side portions the ends of which are pivotally connected to the outer legs, and means on said top guiding the intermediate brace-portion as the outer legs are swung between collapsed and extended positions, the side portions of said brace being shaped to frictionally engage and releasably retain the inner legs when the legs are collapsed.
